UNITED STATES PATENT OFFICE

JOSEPH W. BURGESS AND AUGUST ANSCHUTZ, OF KANSAS CITY, MISSOURI

DESIGN FOR AN IDENTIFICATION CARD OR CERTIFICATE

Application filed November 2, 1931. Serial No. 41,603. Term of patent 7 years.

To all whom it may concern:

Be it known that we, JOSEPH W. BURGESS and AUGUST ANSCHUTZ, both citizens of the United States, residing at Kansas City, in the county of Jackson and State of Missouri, have invented a new, original, and ornamental Design for an Identification Card or Certificate, of which the following is a specification, reference being had to the accompanying drawing, forming a part thereof.

The figure is a face view of the identification card or certificate.

The certificate is printed on suitable stock, the face opposite from the one illustrated being plain.

We claim:

The ornamental design for an identification card or certificate as shown and described.

JOSEPH W. BURGESS.
AUGUST ANSCHUTZ.
